UNITED STATES PATENT OFFICE.

WALTER B. PEARSON, OF CHICAGO, ILLINOIS.

HORIZONTAL DRILLING AND BORING MACHINE.

SPECIFICATION forming part of Letters Patent No. 593,491, dated November 9, 1897.

Application filed December 29, 1896. Serial No. 617,371. (No model.)

To all whom it may concern:

Be it known that I, WALTER B. PEARSON, a citizen of the United States, and a resident of Chicago, in the county of Cook and State 5 of Illinois, have invented certain new and useful Improvements in Horizontal Drilling and Boring Machines, of which the following is a specification.

My invention relates to improvements in 10 horizontal drilling and boring machines, and relates particularly to certain novel features in the construction of the bed and column of the machine, in the means for supporting and operating the table thereof, and to an improved 15 thrust-bearing for the feed mechanism.

Machines of this kind are particularly designed and adapted for heavy duty, and are consequently made very large and heavy.

As heretofore constructed, the column of 20 the machine has been either cast integral with the bed or has been bolted to a thin rearward extension thereof. The first construction is objectionable on account of the large size and great weight of these parts, which renders 25 them difficult to handle and increases the cost thereof. The second construction is also objectionable and for the reason that by reducing the thickness of the bed it is rendered weak and is consequently liable to spring and 30 buckle when resting upon an uneven surface or support, thereby throwing the machine "out of true." As it relates to this feature, the object of the invention is to provide a 35 machine in which the column and bed are made separate from each other and the bed of which will possess desired strength and stiffness.

To this end my invention consists in making the bed of such thickness throughout its 40 entire length as will insure desired strength and stiffness to the machine and in securing a separate column to a lateral extension of said bed, the end of the bed being inclosed by said column, the front of which is cut 45 away to receive said bed.

As heretofore constructed also the table of the machine has been made integral with the vertical slide thereof. As a consequence 50 of this construction and of the great weight of said table and slide, which together form a knee, the fitting of said slide to the ways on the column of the machine has been a very

slow and difficult operation, involving much work and corresponding expense. As it relates to this feature, the object of my invention is to provide a table which may be "trued up" relatively to the spindle of the machine independently of the vertical slide; and to this end the invention consists in making the table separate from the slide and in 55 articulating one end thereof to said slide in any suitable manner, so that said table will be pivotally movable relatively to said slide, and in so supporting said table that the ends thereof may be adjusted vertically independently of each other, and that when said table has been thus adjusted in proper position 60 relatively to the spindle of the machine it may be raised or lowered bodily without impairing its alignment.

In the preferable construction shown the table is secured to the slide by means of a horizontal pivot-pin, and the ends thereof rest upon upright screws, the lower ends of which are threaded through nuts secured in 70 the bed of said machine. To provide for "truing up" the table, one or both of said nuts are movable in the bed, and to provide for raising and lowering said table bodily 75 bevel-gears are secured to said screws, which engage other bevel-gears secured to a shaft supported in suitable bearings in the table.

A further object of my invention is to provide improved means for supporting the outer or free end of the table in adjusted position 80 and for supporting the outer end of a boring-bar, whereby said machine is adapted to a wider range of work than machines of the same size as now constructed. Heretofore the free end of the table and the end of 85 the boring-bar have been supported by means of a single standard, which rests upon the bed of the machine and which comprises two upright arms, the sides of which embrace the sides of the table and the tops of which are 90 connected by a suitable cap, which extends over and across said table. Slots are formed in the upright arms, through which pass binding-screws, the heads of which are secured in T-grooves formed in the sides of 95 the table and to the ends of which, projecting through the slots in said upright arms, are threaded clamping-nuts, and a bearing for the outer end of a boring-bar is formed 100

in the cap connecting the ends of the upright arms of the standard. Said support or standard will thus obstruct the table of the machine and will operate to limit the capacity 5 of the machine to work shorter than the table. As it relates to this feature, my invention consists in supporting the end of the bed by means of separate upright arms, one arranged on each side thereof, and in providing 10 a bearing for the boring-bar in a standard which rests upon the bed of the machine and is located beyond the outer end of the table, thus leaving the table entirely free and unobstructed.

15 A further object of my invention is to provide an improved support for the thrust-bearing of the feed attachment of machines of this kind. Heretofore the bearing for the feed attachment has been formed on a bracket 20 secured to the column of the machine. This construction is objectionable for the reasons, among others, that fitting the bracket to the column involves expense and is weak relatively to the amount of metal used. As it 25 relates to this feature, my invention consists in forming the thrust-bearing for the feed attachment on a rearward extension of the head-stock, which comprises a web or flange on each side thereof so disposed that the 30 thrust of the feed mechanism will subject the same to a direct tensile strain only. The advantages of this construction, as compared with that heretofore used, are that the cost of fitting and attaching a bracket to the column are eliminated and the great relative 35 strength and absolute stiffness and freedom from all spring. A further advantage of my improved construction is that the bearing for the feed attachment may be bored at the same time with the spindle-bearings of the 40 head-stock, thereby insuring absolute accuracy and considerably cheapening that operation.

The invention also consists of the various 45 other features, combinations of features, and details of construction hereinafter described and then pointed out in the claims.

In the accompanying drawings a boring and drilling machine embodying my invention is 50 fully illustrated.

Figure 1 is a side elevation of a horizontal drilling and boring machine embodying my invention. Fig. 2 is a vertical longitudinal sectional view thereof. Fig. 3 is an end view 55 thereof. Fig. 4 is a plan section of the table on the line 4 4 of Fig. 1. Figs. 5, 6, 7, and 8 are details showing the manner of securing the nuts of the adjusting-screws to the bed; and Fig. 9 is a sectional view of the rearward 60 extension of the head-stock on the line 9 9 of Fig. 2.

The following description of my improved drilling and boring machine is limited to a detailed description of the novel features 65 thereof, as those features shown and not so described are old and well known in the art and will be readily and fully understood by

persons familiar with such machines from an inspection of the drawings.

Referring now to the drawings, A designates the bed of the machine, and A' the column thereof. In a machine of my improved construction the bed and column are made separate from each other. The bed A is made of such depth or thickness throughout 70 its entire length as will give desired strength and stiffness to the machine and will insure that the bed will not spring or buckle out of true when resting upon an irregular surface or support. As shown, the bed is made of 75 substantially uniform depth throughout its entire length. The column A' rests upon and is rigidly secured to a lateral extension A², formed around the end of the bed A, the end of the bed being inclosed by the column, a 80 suitable opening a being formed in the front side or wall of said column to receive the bed.

The table B of the machine is made separate from the vertical slide B' and one end of said table is articulated to said slide. In the 85 preferable construction shown the table B is connected to the slide B' by means of a pin B², which has suitable bearings formed in both said slide and table and which is made sufficiently large to insure necessary strength 90 and rigidity of the machine.

The table B rests upon upright screws B³ B⁴, located beneath the same, one adjacent to each end thereof. The upper ends of said screws are secured so as to rotate freely in 100 suitable bearings formed in the under side of the table B, and the lower ends thereof are threaded to nuts B⁵ B⁶, secured in the bed of the machine. The screws B³ B⁴ are of the same pitch, and secured thereto are bevel-gears b b', which mesh with gears b² b³, secured to a shaft B⁷, which extends longitudinally of the table B and is revoluble in suitable bearings therein. The end of the shaft 105 B⁷ projects at the front end of said table and is squared to receive a wrench or a crank. Rotation of said shaft B⁷ will obviously operate to raise or lower the table B and to maintain it always parallel with its initial position. In the preferable construction shown the 110 screws B³ B⁴ project above their bearings in the table B, and the gears b b' are secured to said projecting upper ends of the screws, and openings b⁴ are formed in the top of the table above said gearing. The openings b⁴ are 115 closed by means of removable caps b⁵. Said openings b⁴ render the gearing readily accessible both in assembling and in repairing the same, and the caps b⁵ prevent chips and dirt from falling into said gearing.

As a further improvement in machines of this kind I provide a shaft B⁸ at the pivoted end of the table, a bevel-gear b⁶ on which meshes with the bevel-gear b² on the shaft B⁷. The end of the shaft B⁸ projects beyond the 120 side of the table and is squared in the same manner as is the end of the shaft B⁷. In order that the gear b⁶ shall clear the gear b, it is made to contain fewer teeth than the gear 125

*b*². As a result of this construction the shaft *B*⁸ will project from the side of the table at an angle thereto. A desired relation of parts is as follows: pitch of the gear *b*², five, (5;) 5 number of teeth, twenty, (20;) pitch of the gear *b*⁶, five, (5;) number of teeth, sixteen, (16,) or four less than in the gear *b*². With these proportions it so happens that the shaft *B*⁸ projects in such position that other parts 10 of the machine will not interfere with turning the crank thereon.

The nut *B*⁵ is rigidly secured to the bed of the machine in permanent adjustment. The nut *B*⁶ is revoluble in a suitable bearing 15 formed in the bed of the machine and is secured therein in such manner as to provide for limited rotary movement thereof. As shown, the nut *B*⁶ is fitted to a bushing *B*⁹, rigidly secured to the bed of the machine, 20 and said nut is secured to said bushing by means of bolts *b*⁷, which pass through circular slots formed in the flange of said nut and are threaded into said bushing, all in a familiar manner.

25 It is obvious that by means of the nut *B*⁶ the outer end of the table *A* may be raised and lowered relative to the inner or pivoted end thereof. Said nut thus affords convenient means for truing up said table relatively 30 to the spindle of the machine and to maintain it in such relation.

If for any reason considered desirable, my invention also contemplates making the nut *B*⁵ adjustable instead of the nut *B*⁶, or both 35 of said nuts may be adjustable.

Pivoted one to each side of the table *B*, adjacent to the outer end thereof, are arms *C*, each of which is provided with a slot *c*, through 40 which passes a binding-screw *c*', which is threaded into the side of the bed of the machine. As shown, the upper ends of the arms *C* are secured to the table *B* by means of studs *c*², to the outer ends of which are threaded binding-nuts *c*³. To provide for the 45 convenient removal of the arms *C*, the studs *c*² are provided with heads which engage T-slots *c*⁴, formed in the sides of the table, and the relation of parts is such that the tops of said arms will be below the top of the table. Said 50 arms *C* will obviously operate to support the outer end of the table *B* independently of the screws *B*³ *B*⁴, thus relieving said screws and insuring stiffness and rigidity to said table. In like manner the inner end of said table 55 may be secured in adjusted position independently of said screws by means of a set-screw *c*⁵, which bears against the gib of the slide *B*' and clamps it to the guide on the column *A*' of the machine in the usual 60 manner.

The bearing for the outer end of the boring-bar is formed in the upper end of a standard or column *C*', which rests upon the bed of the machine and is located beyond the 65 outer end of the table *B*.

With a machine constructed in the manner described it is obvious that the top of the

table will be entirely unobstructed by the parts of the machine at all times.

As it relates to the improved thrust-bearing for the feed mechanism which is, as usual, in the rear of the main bearings of the head-stock *D* of the machine, the novel feature of a machine embodying my invention consists in the manner of supporting said bearing. 70 In my improved construction said thrust-bearing is formed at the outer end of a rearward extension *D*' of the head-stock *D* of the machine, which is preferably formed integral with said head-stock and which comprises 80 webs or flanges *d*, which extend up on both sides of the spindle to about the middle thereof, so that the strain due to the feeding of the tool will be mainly sustained by metal disposed in a direct line with the direction of 85 said strain, which is thus subjected to a tensile strain only. As heretofore stated, a further advantage of this construction is that said thrust-bearing may be bored with the main bearings of the head-stock, thus effecting a considerable economy. 90

I claim—

1. In a horizontal drilling and boring machine, or the like, the combination of a slide, a table pivoted thereto and means for raising 95 and lowering the ends of said table independently of each other, substantially as described.

2. In a horizontal drilling and boring machine, or the like, the combination of a slide, a table pivoted thereto, means for raising and 100 lowering the ends of said table independently of each other and means for raising and lowering said table bodily, substantially as described.

3. In a horizontal drilling and boring machine, or the like, the combination of a slide, a table one end of which is pivoted to said slide and means for adjusting said table pivotally, substantially as described. 105

4. In a horizontal drilling and boring machine, or the like, the combination of a slide, a table one end of which is pivoted to said slide, means for adjusting said table pivotally and means for raising and lowering said 110 table and slide bodily, substantially as described. 115

5. In a horizontal drilling and boring machine, or the like, the combination of a slide, a table one end of which is pivoted to said slide, screws beneath said table, one adjacent 120 to each end thereof, the upper ends of which are revolubly secured in said table and the lower ends of which are threaded to nuts secured in the bed of the machine, one or both of said nuts being adjustable and means 125 to rotate said screws together to raise or lower the table bodily, substantially as described.

6. In a horizontal drilling and boring machine, or the like, the combination of a slide, a table one end of which is pivoted to said 130 slide, screws beneath said table, one adjacent to each end thereof, the upper ends of said screws being revolubly secured in said table and the lower ends thereof being threaded

to nuts secured in the bed of the machine, one or both of said nuts being adjustable, a shaft carried in the table, gears on which engage with gears secured to said screws and means to rotate said shaft, substantially as described.

7. In a horizontal drilling and boring machine, or the like, the combination of a slide, a table one end of which is pivoted to said slide, screws beneath said table, one adjacent to each end thereof, the upper ends of said screws being revolvably secured in said table and the lower ends thereof being threaded to nuts secured in the bed of the machine, one or both of said nuts being revolvably secured in bushings secured in the bed, binding-screws which pass through circular slots in said nuts and are threaded into said bushing or bushings, a shaft carried in the table, gears on which engage with gears secured to said shaft, substantially as described.

8. In a horizontal drilling and boring machine, or the like, the combination of a slide, a table one end of which is pivoted to said slide, screws beneath said table, one adjacent to each end thereof, the upper ends of said screws being revolvably secured in said table and the lower ends thereof being threaded to nuts secured in the bed of the machine, gears secured to the upper ends of said screws which engage gears secured to a shaft carried in the table, means to rotate said shaft, openings in said table through which said gearing is accessible and caps to close said openings, substantially as described.

9. In a horizontal drilling and boring machine, or the like, the combination of a slide, a table connected thereto, screws beneath said table, one adjacent to each end thereof, the upper ends of said screws being revolvably secured in said table and the lower ends thereof being threaded to nuts secured in the bed, a longitudinal shaft carried in the table, gears on which engage gears secured to said screws, a transverse shaft revolvably mounted in said table adjacent to the end thereof connected to the slide, a gear on said transverse shaft which engages the gear on the longitudinal shaft at the corresponding end of the table, the gear on said transverse shaft being small enough to clear the gear on the screw and means to rotate said transverse shaft, substantially as described.

10. In a horizontal drilling and boring machine, or the like, the combination of a slide, a table one end of which is pivoted to said slide, screws beneath said table, one adjacent to each end thereof, the upper ends of said screws being revolvably secured in said table and the lower ends thereof being threaded to nuts secured in the bed, a longitudinal shaft carried in the table, gears on which engage gears secured to said screws, a transverse

shaft revolvably mounted in said table adjacent to the pivoted end thereof and which projects at the side of the table, a gear thereon which engages the gear on the longitudinal shaft at the corresponding end of the table, the gear on said transverse shaft being small enough to clear the gear on the screw and means to rotate said transverse shaft, substantially as described.

11. In a horizontal drilling and boring machine, the combination with the table of arms secured to the outer end thereof which do not extend above the top of said table and means to clamp the lower ends of said arms to the bed of the machine, substantially as described.

12. In a horizontal drilling and boring machine, or the like, the combination with the table of arms pivoted to each side thereof adjacent to its outer end, and in such position that they will not extend above the top of said table, slots formed in said arms through which pass binding-screws threaded into the bed of the machine, substantially as described.

13. In a horizontal drilling and boring machine, or the like, the combination with the table of arms pivoted thereto adjacent to its outer end, slots formed in said arms through which pass binding-screws threaded into the bed of the machine, and a bearing for the outer end of a boring-bar formed in a standard or column, which rests upon the bed beyond the end of the table, substantially as described.

14. A thrust-bearing for the feed mechanism of a horizontal drilling and boring machine, formed at the end of a rearward extension of the head-stock of said machine, said rearward extension of the head-stock being formed integral with said head-stock and comprising webs which extend up even with the middle of the spindle on both sides thereof in such manner that they will sustain a tensile strain from the operation of the feed mechanism, substantially as described.

15. In a horizontal drilling and boring machine, the combination of a bed of substantially uniform depth or thickness throughout its entire length, a separate column rigidly secured to an extension formed around one end of the bed adjacent to the bottom thereof, the end of the bed being inclosed by said column and the front wall or side of the column being cut away to receive said bed, substantially as described.

In testimony that I claim the foregoing as my invention I hereunto set my hand this 21st day of December, 1896.

WALTER B. PEARSON.
